(57) **CLAIM**

The ornamental design for a USB hub with media reader, as shown.

DESCRIPTION

A portion of the disclosure of this patent document contains material which is subject to copyright protection. The copyright owner has no objection to the facsimile reproduction by anyone of the patent document or the patent disclosure, as it appears in the U.S. Patent and Trademark Office patent files or records, but reserves all copyright rights whatsoever. FIG. 1 is a perspective view of a USB hub with media reader, in accordance with the present invention.

FIG. 2 is a plan view of a USB hub with media reader, in accordance with the present invention.

FIG. 3 is an underside view of a USB hub with media reader, in accordance with the present invention.

FIG. 4 is a side view of a USB hub with media reader, in accordance with the present invention.

FIG. 5 is a corresponding side view of the USB hub with media reader, in accordance with the present invention.

FIG. 6 is a rear view of a USB hub with media reader, in accordance with the present invention; and,

FIG. 7 is a frontal view of a USB hub with media reader, in accordance with the present invention.
